UNITED STATES PATENT OFFICE.

LEON JOSEPH PRIEBATSCH, OF BROOKHAVEN, MISSISSIPPI.

FRAME FOR BEDS.

Application filed May 12, 1923. Serial No. 638,558.

To all whom it may concern:

Be it known that I, LEON J. PRIEBATSCH, a citizen of the United States, and a resident of Brookhaven, in the county of Lincoln and State of Mississippi, have invented 5 a new and Improved Frame for Beds, of which the following is a full, clear, and exact description.

This invention relates to improvements in 10 frames for beds and has particular reference to a corner lock therefor.

An object of the invention is to provide a frame for beds, which may be readily and quickly assembled and when in such position 15 will form a connection between the side and end rails of the frame, which will impart rigidity thereto.

Another object is to provide a corner lock for the side and end rails of a frame, the 20 separable parts of which are so organized that the same may be readily disassembled to enable the members of the frame to occupy a minimum amount of storing space.

The above and other objects will appear 25 more clearly from the following detail description, when taken in connection with the accompanying drawing, which illustrates a preferred embodiment of the inventive idea.

In the drawing—

30 Figure 1 is a fragmentary perspective view of one corner of a frame constructed in accordance with the invention;

Figure 2 is a top plan view of the bedpost shown in transverse section;

35 Figure 3 is a vertical longitudinal section;

Figure 4 is a fragmentary perspective view of one of the side rails of the frame; and

40 Figure 5 is a fragmentary elevation of the bedpost.

The invention is shown as applied to a frame for beds, but it is to be expressly understood that the invention is susceptible of various applications.

45 Referring particularly to the drawing, 6 indicates one of the bedposts of a bed, said post being of tubular formation and may be made of metal or any other desirable material. Associated with the bedpost 6 is a 50 housing, generally indicated by the numeral 7, and including a web portion or base plate 8 extending longitudinally of the post 6 and having projecting from its vertical edges the side plates 9. The bottom of the housing is formed by a supporting member, gen-

erally indicated by the numeral 10 (Figure 3) and including the top plate 11, the vertical flange 12, the bottom plate 13 and the vertical flange 14 spaced from the flange 12. In assembling the structure the vertical 60 flange of the end rail 15 is engaged with the vertical flange 14 and a fastening device in the form of a bolt 16 is extended through said flanges and also the flange 12 and the base plate 8 for the purpose of securing the 65 parts in assembled position. The head of the bolt 16 extends beyond the base plate 8 and is insertable into the enlarged end of a key-shaped opening 17 formed in the post 6. The portion of the inner surface of the 70 post adjacent the reduced end of the opening 17 is cut away to provide a groove 18 in which is engaged the squared portion 19 of the bolt 16 to prevent turning of the bolt when the housing is supported in position on 75 the post.

Secured to the inner sides of the side plates 9 of the housing adjacent the upper ends thereof and above the top plate 11 of the supporting member 10 are the opposed 80 retaining plates 20 having end portions 21 arranged in parallel and spaced relation with respect to the base plate 8 of the housing, the opposite ends 22 of said retaining plates or members extending diagonally outward and in converging relation. Attached 85 in any suitable manner to the outer adjacent extremities of the portions 22 and extending inwardly in substantially parallel relation are the resilient retaining arms 23 90 designed to engage portions of the side rail 24 to aid in maintaining the same in proper relation to the end rail and bedpost.

Each end rail includes the vertical and horizontal flanges 25 and 26, the latter of 95 which is cut transversely adjacent one end of the rail, as indicated at 27, (Figure 4) to form a side flange 28 which is bent to a vertical position in engagement with the flange 25 and secured thereto by rivets 29, or other suitable fasteners. The extremities of the flanges 25 and 26 are then bent at right angles to form the end flanges 30 which extend in opposite directions with respect to each other to provide a transverse retaining portion which is designed to engage in the space between the ends 21 of the retaining members 20 and the adjacent face of the base plate 8, as best shown in Figure 2. When the rail is being thus engaged in the 100 105 110

housing, the side flange 28 and the portion of the flange 25 engaged thereby are inserted downwardly and between the resilient arms 23 which are spread apart at their ends, 5 together with the free extremities of the portions 22 so that said portions and arms will be placed under tension to frictionally retain the side rail in its proper position. To facilitate the engagement of the flanges 10 25 and 28 between the members 22 and 23 the lower edges of said flanges are beveled, as indicated at 31. When the side rail is in position the horizontal flange 26 thereof and the lower edges of the flanges 25, 28 and 30 15 will rest upon the top plate 11 of the supporting member 10.

It will be obvious from the foregoing description that the frame may be readily disengaged from the posts 6 by first lifting 20 the frame to register the heads of the bolts 16 with the enlarged portions of the openings 17, whereupon said bolts may be withdrawn from engagement with the posts. Then by removing the nuts 32 mounted on 25 the bolts 16 the end rails may be detached from the housings. It will also be understood that the side rails may be disconnected from the housings by lifting the same from engagement with the various retaining members. 30

What is claimed is:

1. In a frame for beds, a corner post, a housing carried thereby and including a web and side plates extending from said web, cooperating retaining elements each of which has an intermediate portion secured to one of said side plates and an end portion extending laterally from said side plate in spaced relation to said web, the other end 35 portions of said retaining elements being arranged in converging relation, and a rail having a portion extending between the converging end portions of said retaining elements and also having other portions engageable between the first named end portions of said retaining elements and said web. 40

2. In a frame for beds, a corner post, a housing carried thereby and including a web, 50 and side plates extending from said web, cooperating retaining elements each of which has an intermediate portion secured to one of said side plates and an end portion extending laterally from said side plate

in spaced relation to said web, the other end portions of said retaining elements being arranged in converging relation, a rail having a portion extending between the converging end portions of said retaining elements and also having other portions engageable between the first named end portions of said retaining elements and said web, and resilient retaining members having adjacent ends secured to the converging ends of said retaining elements and between 55 which the first named portion of said rail is engaged. 60

3. In a frame for beds, a corner post, a housing supported thereby, retaining members within said housing, and a rail including vertical and horizontal flanges, the vertical flange having its extremity bent to provide an end flange and the horizontal flange being cut to form a side flange in engagement with said vertical flange, said 75 horizontal flange being also bent at its extremity to provide a second end flange, said end flanges being engageable between said retaining members and a portion of said housing, and said vertical and side flanges being 80 engageable between said retaining members. 85

4. In a frame for beds, a corner post, a housing, a supporting member formed in the bottom of said housing, retaining members in said housing above said supporting member, a rail, means for attaching said rail to said supporting member and engageable with said bedpost to support the frame in operative position, and a second rail having a portion engaged between said retaining members and another portion between 90 said retaining members and a portion of said housing. 95

5. In a frame for beds, a corner post, a housing supported thereby and including a web, side plates extending from said web, a bottom for said housing, a rail supported on the bottom of said housing and having laterally extending end portions engageable with said web and an adjacent portion extending between said side plates, and retaining elements carried by said side plates on opposite sides of the second named portion of said rail and having adjacent ends engageable with said second named portion 105 and opposite ends engageable with the first named portions of said rail. 100

LEON JOSEPH PRIEBATSCH.
